CLAIM

The ornamental design for an embedded lighting device, as shown and described.

DESCRIPTION

FIG. 1 is a perspective view of the lighting equipment according to the present invention;

FIG. 2 is a frontal view of the lighting equipment according to the present invention;

FIG. 3 is a side view of the lighting equipment according to the present invention which is the mirror image of the opposite side view of the present invention;

FIG. 4 is a top view of the lighting equipment according to the present invention which is the mirror image of the bottom view of the present invention; and,

FIG. 5 is a rear view of the lighting equipment of the present invention.

The broken lines illustrate portions of the embedded lighting device which form no part of the claimed design.
